SAMUEL REICH, OF BROOKLYN, NEW YORK.

PAPER BAG.

Application filed July 5, 1927. Serial No. 203,483.

This invention relates to paper bags of the household marketing type used for transporting merchandise, having a foldable bottom and one or more endless cord means for supporting the bag from the bottom and forming the handles for said bag.

Bags of this general type are extensively used by shoppers and in many instances are distributed to customers making large purchases by grocers and other retail produce merchants. In the bags now in use, however, the bottoms are merely formed by overlapping the flaps formed from the same material as the body portion and sealing these as in an ordinary paper bag. Such bottoms are often insecure and unable to sustain the weight of heavy merchandise, particularly if they become wet for any reason.

Bags of this general type have also had their supporting means extending around the bottom of the bag or diagonally across same, either entirely or partially on the outside, thus rendering the cords liable to be caught and torn from the bag with resultant injury to the bag and possible damage to the contents.

An object of the present invention is to provide a bag suitable for carrying heavy merchandise without materially increasing the weight of the bag as by inserting a reinforcing bottom member whereby even though the inner bottom should become wet as through a leak in one of the packages within the bag, the outer bottom would remain dry for a considerable time as the moisture would be wholly or partly absorbed by the reinforcing member.

A further object of the invention is to provide a bag of the type described wherein the endless cord means supporting the bottom of the bag are entirely covered by the overlapping flaps forming said bottom.

Another object is to provide a bag having the seam of the body portion extending along one edge thereof, thereby making it possible to print advertising matter on both sides of the bag at a single operation prior to the bag being assembled.

With the above and other objects in view, my invention consists in a paper bag of the kind hereinbefore referred to, illustrated in the accompanying drawings and hereinafter more specifically described and claimed.

Referring to the drawings:

Fig. 1 is a view in perspective of my preferred form of bag.

Fig. 2 is a longitudinal sectional view of the bag in the vertical plane containing line 2-2 of Fig. 1.

Fig. 3 is a plan view of the bottom of a preferred form of the bag before folding over and sealing the flaps.

Fig. 4 is a plan view of a blank for forming the bag, showing the creases and the cord threading apertures.

Fig. 5 is a plan view of the reinforcing blank showing the creases and the cord threading apertures.

In the drawings, in which like numerals designate similar parts throughout the views, A represents a bag, constructed according to a preferred form of my invention, seamed at 1 along one edge thereof, the joining of the paper being done in such a manner as to make the front and back of the bag alike, which is accomplished by concealing the seam inside the bag, thereby giving a full unbroken surface for printing. Separate endless cord means 2 are threaded through apertures 3 in both sides of the bag adjacent the upper end 80 of the bag, and through apertures 4 spaced from the bottom of the bag, and also through apertures 5 at the intersection of the sides with the bottom. The upper portions of said cord means form handles 6 and the lower portions 7 support the bottom 8. The cords are so arranged that they extend downwardly within the bag between the upper and lower apertures 3 and 4. The manner of attaching the endless cords is clearly shown in Fig. 1. Fig. 4 shows a blank creased ready for forming the bag, the creases 19 of each wall A being creased oppositely to each other. The bag is folded longitudinally along one edge of the seam 1 and also along a line 17 at the opposite side of the bag thus enabling the walls AA to be folded flatly against each other.

The bottom 8 is adapted to be folded upwardly about the creased line 18 against one side of the wall A of the bag, facilitating packing and stacking of the bags. The bottom 8 is formed by displacing the lower portion B along the line 18 so as to dispose the same in a superimposed position upon the wall A. This displacement of the lower portion B will cause the corners 19 (owing to the creases 20 of each wall A being oppositely disposed), to fold inwardly thus forming a triangular pocket 9 at each end when the portion B lies superimposed upon the wall A, as will be seen in full lines from Fig. 3.

When the bottom of the bag is folded in this manner, a reinforcing member C of hexagonal form conforming in size and shape to the bottom 8 is then inserted within the triangular pockets referred to and laid along said bottom. The said reinforcing member and said inwardly folded portions 9 are provided with apertures 9^a therein which are cut so as to register with the apertures 5 in the side 10 of the bag adjacent the bottom and the flap portions 11 and 12 of the folded bottom including corresponding flap portions 13 and 14 of the reinforcing member are then folded inwardly along the lines 15, 16 of said 15 perforations, so as to overlap each other slightly, as shown in chain dotted lines in Fig. 3, and then sealed. The reinforcing member may consist of any suitable fibrous material such as cardboard, preferably considerably thicker 20 than the material of which the bag is made.

The lower portions 7 of the endless cord means 2 after being threaded through the apertures 5 at the bottom of one side of the bag and through the coinciding apertures 9^a 25 in the reinforcing member may extend transversely across the bottom or diagonally across same to the apertures in the opposite side of the bottom, but preferably said lower portions extend longitudinally of the bottom 30 between the apertures along the lines of fold 15, 16 of the reinforcing member 10. Thus, when the flap portions 11 and 12 of the bottom including the corresponding flap portions 13 and 14 of the reinforcing member 35 are folded inwardly along the lines 15, 16 the supporting means will be located between the main portion of the reinforcing member and the said flaps and will be entirely covered by said flaps, as clearly shown in Fig. 2.

It will be obvious from the foregoing description of my invention that I have provided a bag of unusual strength capable of sustaining considerable weight, as well as a bag that is more valuable from an advertising 45 standpoint because of the facility by

which it may be printed on both sides at a single operation.

Further the reinforcing member being applied in the manner indicated covers the entire bottom of the bag and makes at the weakest point a 3-ply bottom and at the strongest point namely centrally of the bottom, a 5-ply bottom. Secured as it is by inwardly folding, it will support the contents of the bag even though the contents were of such character as to dissolve the bottom glue entirely, while the bags now made have only a two ply bottom without reinforcement, and if the paste is dissolved there is nothing to prevent the contents from dropping through. 55

Various changes may be resorted to provided they fall within the spirit and scope of the invention as defined by the appended claims.

I claim:

1. A paper bag of the kind hereinbefore referred to comprising a body portion, a foldable bottom, a foldable reinforcing member located between the top and bottom folds of said bottom, cord supporting means, the lower 70 portions of such means extending longitudinally of the bottom of the bag between the folds of said reinforcing member along the lines of the folds thereof.

2. A paper bag of the kind hereinbefore referred to comprising a body portion consisting of two side members joined by a seam along one edge of the bag, a foldable bottom, a reinforcing member for said bottom having folded portions cooperating with folded portions of said bottom, two endless cord supporting means threaded through said side members and through said reinforcing members, the upper portions of such means extending above the side members and the lower 85 portions extending longitudinally of the bottom of the bag between the folded portions of said reinforcing member.

In testimony whereof I affix my signature.

SAMUEL REICH.
